CLAIM

The ornamental design for a golf club head, as shown and described.

DESCRIPTION

FIG. 1 is a perspective view of a golf club head showing our new design;

FIG. 2 is a toe end view of the golf club head shown in FIG. 1;

FIG. 3 is a heel end view of the golf club head shown in FIG. 1;

FIG. 4 is a top view taken along the lines 4—4 in FIG. 2;

FIG. 5 is another top view taken along the lines 5—5 in FIG. 3;

FIG. 6 is a bottom view of the golf club head shown in FIG. 1;

FIG. 7 is a front elevational view of the golf club head shown in FIG. 1; and,

FIG. 8 is rear elevational view of the golf club head shown in FIG. 1.

The broken line showing the grooves of the striking face is for illustrative purposes only and forms no part of the claimed design.
